UNITED STATES PATENT OFFICE

111,771

DESIGN FOR A COMBINED TUBE DISPENSER AND ARTICLE HOLDING DEVICE

William L. Kennedy, Denver, Colo.

Application August 8, 1938, Serial No. 79,182

Term of patent 7 years

To whom it may concern:

Be it known that I, William L. Kennedy, a citizen of the United States, residing in the city and county of Denver, and State of Colorado, have invented a certain new, original, and ornamental Design for a Combined Tube Dispenser and Article Holding Device, of which the following is a specification, reference being had to the accompanying drawing, forming part thereof.

Figure 1 is a front elevational view of a combined tube dispenser and article holding device, showing my new design;

Figure 2 is a side elevational view thereof.

I claim:

The ornamental design for a combined tube dispenser and article holding device, as shown.

WILLIAM L. KENNEDY.
